RELAXATION OSCILLATOR

Harry R. Lubeke, Los Angeles, Calif.

Application May 23, 1934, Serial No. 727,100

11 Claims. (Cl. 250—36)

In the following specification, and the accompanying drawing, I describe and show preferred means for accomplishing the objects of my invention. I do not limit myself to the means disclosed however, and various changes and adaptations may be made without departing from the essence of the invention as hereinafter claimed.

My invention relates to the art of television, and particularly to methods and means for the production and synchronization of wave forms suitable for television scanning.

For electrical scanning by a television receiver of the cathode ray type, it is most desirable to be able to impress thereon sawtooth waveforms of electrical energy. Such waveforms may be applied to the means for deflecting the cathode rays, in well known ways; to cause the stream of electrons, and the light spot produced on the fluorescent screen thereby, to execute traverses across the receiving screen, synchronously with similar traverses across the field of view at the transmitter.

The prior art has been limited hitherto to sources of scanning energy which include several cooperating thermionic devices of the high vacuum type, when high quality results are desired; or to the use of single gaseous-discharge tubes, when inferior scanning waveforms can be tolerated.

In my co-pending application No. 526,282, filed March 30, 1931 I disclosed a source of scanning energy that is capable of producing a high quality output; that is to say, a source having an output of sawtooth wave-shape. In that output, the sloping sawtooth rises of the wave-shape are almost rectilinear; and the connecting portions are very steep, and consume relatively very small time intervals. But, to accomplish such results, by the method of that disclosure, three separate thermionic tubes are required.

The limitations of single gaseous discharge tubes; in which the deionization time of the gas limits the rapidity of the return portions of the waveform between the peaks; and in which the self-initiation of the time-constant circuit, in starting the successive waves, precludes a time-constant value that gives good linearity; are known to those skilled in the art.

An object of the present invention is to provide a single tube high vacuum thermionic source of scanning energy, that combines the advantages of multtube high vacuum devices with the simplicity of single tube devices.

Another object is to provide an oscillator of

the single tube multi-vibrator or relaxation type, in which the frequency of oscillation is independent of cathode emission.

A third object of the invention is to provide an oscillator having dynatron characteristics, wherein the emission and wattage dissipation of usual thermionic devices is not exceeded.

My objects have been attained in the manner illustrated in the accompanying drawing, in which—

Fig. 1 is a diagrammatic representation of my improved source of energy for television scanning;

Fig. 2 is a diagram illustrating the relation of the several electrode currents of my thermionic device to the inner grid voltage thereof; and

Fig. 3 shows the voltage waveforms that appear at the several electrodes of my thermionic device.

Referring to Fig. 1, reference numeral 5 indicates the envelope of my single high-vacuum thermionic device. This includes; an electron-emitting cathode K, that is heatable by a battery 6; three grids, G₁, G₂, and G₃ respectively; and an anode or plate P. The last mentioned electrodes, in actual construction, preferably should surround the cathode; grid G₁ being closest to the cathode; grid G₂ being at a greater distance therefrom, and therefore of larger diameter; grid G₃ being still farther from the cathode, and the largest in diameter; and plate P enclosing all of the other electrodes in the device.

One terminal of a resistor 7, and one side of a condenser 8, are connected to each other and to grid G₁, by a conductor 9. The other terminal of the resistor is connected to cathode K and to ground; and the other side of condenser 8 is connected to grid G₃ by a conductor 23. This arrangement forms a time-constant circuit that largely determines the frequency of oscillations of the device. Grid G₂ is connected at 11 to the highest positive voltage tap of a battery 12, or other source of voltage, through a resistor 13. The latter usually may be of small value, or even may be omitted under some conditions. Thus grid G₂ serves largely as a means for accelerating electrons, in their flight from the cathode. Grid G₃ is connected to a considerably lower voltage tap of battery 12 at 14, through a resistor 15. This last mentioned grid thus has a potential that is considerably lower than that of grid G₂, and it is adapted to emit secondary electrons. Consequently it is able to coact with grid G₁, through condenser 8 to maintain relaxation oscillations. Plate P is connected, through

a resistor 16, to an intermediate voltage tap 17 on battery 12. A condenser 18 is connected between plate P and cathode K, or directly in shunt to resistor 16; and, in cooperation with resistor 16, forms a second time-constant circuit that is adapted to modify the relaxation oscillations described supra. The energy wave-shape, resulting from this arrangement, has a sawtooth form with nearly rectilinear upward slopes, and rapid return traces connecting the peaks.

An alternating current generator, indicated at 19, schematically represents any source of short and sharp energy pulses, that are repeated at a frequency at or near the natural frequency of the relaxation oscillations of the described apparatus. Such pulses may occur in connection with a constant television scanning operation for example, and be in sympathy with it. A conductor 21, which should be considered as being diaphragmatic of any communication means for transmitting such pulses, and therefore is shown dotted for a part of its length, establishes communication between generator 19 and grid G₃. Synchronizing pulses also may be applied, if desired, to grids G₁, or G₂, or to plate P.

The lower part of resistor 7 is shown as being variable, to permit adjusting the natural frequency of the device to approximately the frequency of such incoming pulses as those described.

Energy from the above described scanning source may be delivered through conductor 22.

Relaxation oscillations are produced by the device described, because of the dynatron, or secondary emission, characteristic of grid G₃. Such oscillations are responsible for the superior operation of the device as a source of scanning energy. The action may be explained as follows:

Assume, at first, that cathode K is inoperative, 40 and that it is not emitting electrons. Condenser 8 will then assume a charge, by reason of its connection to tap 14 on battery 12. At equilibrium, no current will flow, and therefore no voltage drop will occur in resistors 7 and 15. It will be seen that this puts the potential of grid G₁ at zero, with respect to the cathode and ground.

Assume, next, that cathode K is put into operation, and that it emits electrons. By referring to Fig. 2, which shows how the electrode currents 50 of the device vary with respect to the potential of grid G₁, it will be noted that when the potential of grid G₁ is zero (i. e. at origin O), a large negative current will flow from grid G₃. This is the result of the secondary electron emission of the grid. This negative current will raise the potential of grid G₃ above that of tap 14 by reason of the potential drop in resistor 15. Consequently the upper plate of condenser 8 will become more positive also, since it is directly connected to grid G₃ by conductor 23. The lower plate of condenser 8 naturally will simultaneously become more negative, in order to balance the charge on the upper plate. Therefore the potential of grid G₁ becomes more negative also, since 60 it is connected to the lower plate by conductor 9. As a result of this condition there will be an electronic surge from ground, through resistor 7, condenser 8, grid G₃, resistor 15, and battery 12. Electrons will flow from grid G₃ to grid G₂, since 70 the latter is at a considerably higher potential, and therefore is able to attract a large part of the secondary emission from grid G₃. With these two electronic paths in parallel, condenser 8 quickly becomes charged, and grid G₁ assumes a relatively large negative potential. It will be

seen from Fig. 2, that the above described actions will next cause the secondary emission current from grid G₃ to reduce to zero; and the same thing is substantially true of all the other electrode currents.

The curves of Fig. 3 show how the potentials on the several electrodes vary throughout the operating cycle of the device; slightly more than one complete cycle of each potential waveform being shown, substantially as it would appear on an oscilloscope. At the above stated point in the operating cycle when the thermionic device becomes inactive, the charge on condenser 8 leaks off to ground through resistor 7; and the potential of grid G₁ thus becomes less negative, and approaches zero with respect to the cathode. This action is governed by the exponential discharge curve of the condenser, and corresponds with curve e—G₁ of Fig. 3 between the points 25 and 26.

Referring again to Fig. 2, and remembering that the cathode is now being considered as emitting, we see that, as grid G₁ approaches zero potential, an electronic current starts to flow from cathode K to this grid. This is indicated by curve I—G₁. This current, flowing through resistor 7, causes grid G₁ to become negative, and halts the positive swing thereof. Furthermore, grid G₃ is now emitting secondary electrons, and is further causing grid G₁ to become negative. These combined agencies make grid G₁ quickly swing to a large negative value.

It will be noted that the operating cycle of grid G₁ carries it from a large negative potential, of a value determined by the efficacy of the 35 agencies operating to charge condenser 8, and under which conditions the thermionic device is inoperative; to a value slightly beyond zero potential, where the current from grid G₁, and the secondary emission from grid G₃, reverse the 40 cycle. Thus (referring to Fig. 2) the value of the potential on grid G₁ moves along the horizontal axis (abscissae) from the left, to a point to the right of the vertical axis (ordinates). It does this at a comparatively slow rate during the discharge of condenser 8, and at a rapid rate during the charge thereof. The actual variation of potential on grid G₁ is shown by curve e—G₁ of Fig. 3.

It will be apparent from the foregoing, that 50 my thermionic device does not continuously work at large saturation currents, in the manner that is characteristic of single tube multivibrators or relaxation oscillating devices. In a test of a typical device of my improved form, the average currents drawn from cathode K, as measured with direct current instruments, were $IG_2 = +.8$ m. a.; $IG_3 = -.11$ m. a.; and $Ip = +.75$ m. a.; giving a total of 1.44 m. a., with a useful output of 20 volts, peak to peak, of alternating current wave- 60 form, the frequency being 1,200 cycles. The normal rating of the thermionic device, used as an amplifier, was 2.5 m. a., and the cathode was of a size and rating allowing a current of 5 m. a. when coaxing with a triode arrangement of ele- 65 ments. Typical values for the taps on battery 12, were; for tap 11, 170 volts; for tap 14, 67 volts; and for tap 7, 110 volts.

By suitably varying the capacitance of condenser 8, or the resistance of resistor 7, outputs of 70 from 2 to 75 volts peak to peak may be obtained at frequencies from 6000 to 120 cycles per second. Of course, any frequency and output can be achieved, by a proper choice of values for the respective elements.

In the prior art, the dependence of operating frequency upon cathode emission, and the practical impossibility of maintaining a desired frequency stability, because of this effect, are well known. In my now disclosed device, repeated tests have shown that the frequency of operation is constant within about 2%; while the cathode supply voltage is decreased from its rated value, to 64% of its rated value. At the latter point 10 the device ceases to operate.

While my invention resembles certain prior devices in some ways, it is essentially different therefrom in the respects mentioned, and in certain other respects. These essential differences 15 enable it to function in a superior manner that has not been attainable by ways that have been known hitherto. Thus, Fig. 2 indicates that plate current $I-P$ is almost independent of the voltage of grid G_1 . The plate, being thus uncontrolled by the inner grid, is free to respond to the impulses of outer grid G_3 , (see curve $e-G_3$ of Fig. 3) and its output is a sawtooth wave like that shown at $e-P$ in Fig. 3. This fact, and the further fact that the time-constant value of 20 elements 16 and 18 exercise a definite, although secondary effect, upon the frequency of operation of my device, shows that it enters into the relaxation oscillation process; and that it functions in a manner that could not be attained by 25 additions to devices of the prior art. The difference in operation over prior art devices is further evidenced by the fact that the direct current potential of the anode also affects the 30 frequency of my device.

The voltage waves shown in Fig. 3 bear a striking resemblance to corresponding oscillograms taken from a three tube scanning source like that described in my pending patent application referred to supra. Thus, with reference to said 40 pending application, the present curve $e-G_1$ is very similar in shape and phase to the grid potential curve of the first multivibrator tube disclosed in that application. Correspondingly, curve $e-G_2$ is similar to the plate potential curve 45 of the first multivibrator tube, and to that of the grid of the second multivibrator tube; curve $e-G_3$ is similar to the plate potential curve of the second multivibrator tube; and curve $e-P$ is similar to the plate potential curve of the third, 50 or peaking tube.

The same time scale is used in all of the curves of Fig. 3. Thus, corresponding points in curves vertically above each other occur at the same time in the operating cycle. The heavy lines of 55 the waveforms of Fig. 3 indicate a comparatively slow change of potential with time, as in $e-G_1$ from point 25 to point 26; whereas the light lines indicate a rapid change, as from point 27 to point 28. This is as the waveforms appear in cathode 60 ray oscilloscopes.

From the foregoing disclosure, it will appear that the present invention comprises a new combination of elements that are so arranged and connected as to adapt them to secure, in a single thermionic device, results that could only be attained hitherto by the use of several tubes. Moreover, my present device functions in an entirely new way, in that it makes effective use of 65 secondary emission from grid G_2 . It is a relaxation dynatron oscillator that employs resistive and capacitative elements only. It is notable that curve $I-G_3$ shows that the entire operating range of the current value in grid G_3 may be 70 wholly the result of a secondary emission cur-

rent (the net electron flow always being from the electrode, rather than to it).

In the foregoing description, I necessarily have disclosed specific means whereby the stated objects of my invention may be attained; but the 5 invention is not to be considered as limited to the use of such specific means, except as expressed in the appended claims.

Having thus fully described my invention, I claim—

1. An energy source which includes a thermionic device having a cathode, an anode, and three grids; the cathode and the grid nearest thereto being connected to each other; the next grid in order being connected to a source of positive 15 voltage; the third grid in order being connected to the first said grid through a condenser, and also to a source of positive voltage of less value than that first mentioned; and the anode being connected to the cathode through a condenser, 20 and also to a source of positive voltage that is intermediate in value with respect to the first and second sources mentioned.

2. An electrical energy source which includes a thermionic device having a cathode, an anode, 25 and three grids; the cathode being connected to ground; the grid nearest the cathode being connected to ground through a resistor; the next grid in order being connected to a source of positive voltage; the third grid in order being connected to the first said grid through a condenser, 30 and also being connected through a resistor to a source of positive voltage of less value than that first mentioned; and the anode being connected to ground through a condenser, and also 35 being connected through a resistor to a source of positive voltage that is intermediate in value with respect to the first and second sources.

3. A source of oscillating energy which includes a thermionic device having a cathode, an 40 anode, and three grids differently spaced between the cathode and the anode; the cathode being connected to ground; the grid nearest the cathode being connected to ground through a resistor; the intermediate grid being connected to a source of positive voltage; the grid nearest 45 the anode being connected to the first said grid through a condenser, and also being connected through a resistor to a source of positive voltage of less value than that first mentioned; and the anode being connected to ground through a condenser, 50 and also being connected through a resistor to a source of positive voltage that is intermediate in value with respect to the first and second voltage sources mentioned; the last said 55 grid being adapted to emit secondary electrons, and to thereby cause said device to operate as an oscillator.

4. An oscillator comprising; a thermionic device having a cathode, an anode, and three intermediate grids; and a source of direct current energy of which the negative terminal is connected to the cathode; the cathode and the grid nearest thereto being connected to each other through a resistor; the second grid in order being connected to a positive terminal of said source; the third grid being connected to the first grid through a condenser, and also through a resistor to a positive terminal of said source at a potential level below that of the connection to the 60 second grid; and the anode being connected to the cathode through a second condenser, and also to a positive terminal of said source; the constants of the oscillator being of such value 65 that the third grid is adapted to emit a sec- 70 75

ondary electronic current of greater value than it can receive from the cathode, throughout the operating cycle of the oscillator.

5. An oscillator comprising; a high vacuum thermionic device having a cathode, an anode, and three intermediate grids; and a source of direct current energy of which the negative terminal is connected to the cathode; the cathode and the grid nearest thereto being connected to each other through a resistor; the second grid in order being connected to a positive terminal of said source; the third grid being connected to the first said grid through a condenser, and also being connected through a resistor to a positive terminal of said source at a potential level below that of the connection to the second grid; and the anode being connected to the cathode through a condenser, and also to a positive terminal of said source at a potential level intermediate the connections to the second and third grids; the constants of the oscillator being of such value that the third grid is adapted to emit a sawtooth pulses of electrical energy in said condenser.

6. An oscillator as defined in claim 5, wherein the constants of the oscillator are so chosen that the anode current is made independent of the potential of the first said grid by virtue of said secondary emission.

7. An oscillator comprising; a thermionic device having a cathode, an anode, and three intermediate grids; and a source of direct current energy of which the negative terminal is connected to the cathode; the cathode and the grid nearest thereto being connected to each other through a resistor; the second grid in order being connected to a positive terminal of said source; the third grid being connected to the first grid through a condenser, and also through a resistor to a positive terminal of said source; and the anode being connected to the cathode through a second condenser, and also to a positive terminal of said source; the operating periodicity of the oscillator being controllable by varying the position of the last said terminal with respect to its potential level, to regulate the electronic current flowing in said device and thus to limit the charging currents to the respective condensers.

8. A relaxation oscillator comprising; a high vacuum thermionic device having a cathode, an anode, and three intermediate grids; and a source of direct current energy of which the negative terminal is connected to the cathode; the cathode and the grid nearest thereto being connected to each other through a resistor; the second grid in order being connected to a positive terminal of said source; the third grid being connected to the first grid through a condenser, and also through a resistor to a positive terminal of said source at a potential level below that of the connection to the second grid; and the anode being connected to the cathode through a second con-

denser, and also, through a resistor, to a positive terminal of said source; the periodicity of the relaxation pulses of the oscillator being controllable by varying the time constant of the anode circuit.

9. A relaxation oscillator comprising; a single high vacuum thermionic device having a cathode, an anode, and three intermediate grids; and a source of direct current energy of which the negative terminal is connected to the cathode; the cathode and the grid nearest thereto being connected to each other through a resistor; the second grid in order being connected to a positive terminal of said source; the third grid being adapted to emit secondary electrons, and being connected through a resistor to a positive terminal of said source at a potential level below that of the connection to the second grid; the anode being connected to the cathode through a condenser, and also to a positive terminal of said source; and means for impressing electric pulses upon the third grid to change its potential, and thereby to vary the secondary emission therefrom to control the periodicity of the oscillator.

10. An oscillator comprising; a thermionic device having a cathode, an anode, and three intermediate grids; and a source of direct current energy of which the negative terminal is connected to the cathode; the cathode and the grid nearest thereto being connected to each other through a resistor; the second grid in order being connected to a positive terminal of said source; the third grid being connected to the first grid through a condenser, and also, through a second resistor, to a positive terminal of said source at a potential level below that of the connection to the second grid; and the anode being connected to the cathode through a second condenser, and also to a positive terminal of said source at a potential level intermediate the connections to the second and third grids; the third grid being adapted to emit secondary electrons when the first condenser has become partially discharged, thus permitting that condenser to become re-charged.

11. A relaxation oscillator comprising; a high vacuum thermionic device having a cathode, an anode, and three grids that are differently spaced in relation to the cathode and anode; and a source of direct current energy of which the negative terminal is connected to the cathode; the cathode and the grid nearest thereto being connected to each other through a resistor; the second grid in order being connected to a positive terminal of said source; the third grid being connected to the first grid through a condenser, and also to a positive terminal of said source; and the anode being connected to the cathode through a second condenser, and also to a positive terminal of said source at a potential level intermediate the connections to the second and third grids; the periodicity of the relaxation pulses of the oscillator being controllable by varying the value of the time constant of the resistor and first condenser combination.

HARRY R. LUBCKE.
